DESIGN FOR A CABINET FOR VENDING MACHINES

George A. Gast, Chicago, Ill., assignor to Plane-
tellus Manufacturing Corporation, a corpora-
tion of Illinois

Application July 15, 1935, Serial No. 57,653

Term of patent 7 years

To all whom it may concern:

Be it known that I, George A. Gast, a citizen of the United States, residing at Chicago, in the county of Cook and State of Illinois, have invented a new, original, and ornamental Design for a Cabinet for Vending Machines, of which the following is a specification, reference being had to the accompanying drawing, forming part thereof.

The figure is a perspective view of a cabinet for vending machines, showing my new design.

The opposite side of the design is of substantially the same appearance as the side shown.

I claim:

The ornamental design for a cabinet for vending machines, as shown and described.

GEORGE A. GAST.
